(57) **CLAIM**

The ornamental design for a light bar as shown and described.

DESCRIPTION

FIG. 1 is a front perspective view of the light bar, according to a first embodiment;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof;

FIG. 7 is a bottom plan view thereof;

FIG. 8 is another front perspective view of the first embodiment positioned on a vehicle;

FIG. 9 is a front perspective view of the light bar, according to a second embodiment;

FIG. 10 is a front elevation view of the light bar of FIG. 9;

FIG. 11 is a rear elevation view of the light bar of FIG. 9;

FIG. 12 is a right elevation view of the light bar of FIG. 9;

FIG. 13 is a left elevation view of the light bar of FIG. 9;

FIG. 14 is a top plan view of the light bar of FIG. 9;

FIG. 15 is a bottom plan view of the light bar of FIG. 9; and,

FIG. 16 is another front perspective of the second embodiment positioned on a vehicle.

The broken lines are included for the purpose of illustrating environment and portions of the light bar that form no part of the claimed design.

1 Claim, 14 Drawing Sheets
